UNITED STATES PATENT OFFICE.

GÜNTHER KRAWINKEL, OF GUMMERSBACH, GERMANY.

HIGH-FREQUENCY MACHINE.

Application filed August 15, 1921. Serial No. 492,512.

To all whom it may concern:

Be it known that I, GÜNTHER KRAWINKEL, a citizen of the German Republic, residing at Gummersbach, Germany, have invented certain new and useful Improvements in High-Frequency Machines (for which I have filed application in Germany, March 23, 1920, Patent No. 357,228, granted May 22, 1922; England, May 30, 1921; France, March 21, 1921), of which the following is a specification.

The object of the present invention is to provide an electric generator capable of producing an alternating current of very high frequency and high E. M. F., with a comparatively low speed of operation. For carrying out this object I provide a machine comprising two disks standing with their plane parallel surfaces the one opposite the other and each carrying a number of coil crowns in radial arrangement. One of said disks carries an exciting winding for continuous current which produces an alternating current in the opposite winding of the adjacent disk by the revolving motion communicated to this disk or by the movements of both disks in opposite directions. This alternating current passes through the leads into the next following radial coil crown and excites by induction an alternating current of increased frequency in the coil crown of the first disk which follows next in radial direction, said first disk carrying also the exciting winding for continuous current. The alternating current of higher frequency thus produced is conducted by leads into the following coil crown upon this disk and excites in the opposite coil crown of the other disk an alternating current of again increased frequency which is conducted into the next following coil crown of this second disk to produce an exciting action in the corresponding opposite coil crown of the first disk and so forth. In each coil crown two adjacent coils are wound in opposite directions. If the one coil is wound clockwise the adjacent coil is wound counter-clockwise.

The excitation of alternate coil crowns carried by the two parallel disks may be aptly compared to the reflection of the image of an object between two parallel mirrors. As the image of an object between two parallel mirrors is reflected from one mirror to the other, so the excitation of

the outer coil crown is reflected through the induced and inducing coils from one disk to the other. This mirror-excitation in crowns of coils of two parallel disks with radial arrangement of the two coil crowns upon each disk presents the following advantages.

If the continuous current exciting winding is arranged on the extreme crown, the windings can be made of a wire of large cross section so that these windings can take up currents of comparatively high intensity. The space at disposal diminishes from the circumference of the disks towards the center. As the intensity of current decreases however with the increase of frequency the construction adapts itself naturally to these conditions. The cross section of the wires can therefore be adapted to the different intensities of current by the varying sizes of the coils, the number of turns remaining always the same. As however the exciting current can be chosen very great, sufficient space for the thick wire turns being at disposal in the outer crown, the intensity of the current taken off from the last of the excited crowns will be considerably higher than with axial succession of the reflecting steps.

In comparison with the radial arrangement in one plane the advantage is obtained that the rotor and the stator in the arrangement according to this invention have more turns for the same number of poles, number of revolutions, dimensions and size of wire of the coils. This means that the electro-motive force is greater than with the uni-plane arrangement. Owing to the utilization of two parallel planes having each the radial arrangement of the coils an increased watt efficiency is obtained.

In order that the invention may be clearly understood I shall proceed to describe the same with reference to the accompanying drawing, wherein:—

Figs. 1 and 2 illustrate diagrammatically the two disks *a* and *b* which are supposed to revolve at equal angular speed in opposite directions.

Fig. 3 shows, partly in longitudinal section and partly in side elevation, a form of execution of the invention according to the diagram Fig. 1.

Fig. 3^a is a diagrammatic view illustrating the windings on the two disks and connections between the same.

Fig. 4 shows in which manner several

machines, each consisting of a pair of disks, are to be coupled.

The coils of the crown r^2 of disk a in Fig. 1 serve to take up the exciting continuous current. In the crown of coils R^1 of the adjacent disk b an alternating current is produced which passes through leads into the coils of crown R^2 which follows in radial direction to produce an alternating current 10 of increased frequency in the inner crown r^2 of disk a .

Fig. 2 shows four crowns upon each disk a, b . The alternating current from crown r^2 of disk a , produced in the hereinbefore 15 explained manner, flows over into the third crown r^3 of disk a in order to produce an alternating current of again increased frequency in the third crown R^3 of disk b . This alternating current flows from crown 20 R^3 into the fourth crown R^4 of disk b and produces in the opposite crown r^4 of disk a an alternating current of double frequency. This can be continued with continuous increase of the frequency.

25 The diagrammatical illustration shows that the spaces for the coils get narrower from the circumference to the center. As the intensity of current is however reduced also in the same direction the construction 30 adapts itself very well to the electric conditions.

It is not necessary that the current be taken from the inner coil crown with the highest frequency but current can be taken 35 also from the intermediate crowns so that various wave lengths can be produced simultaneously with one and the same machine.

Disk a with the crowns r^2 and r^2 is keyed upon the shaft w^1 journaled in the standards d and d^2 . The leads which connect the collector rings g^1 and g^2 for the continuous current with the coils of crown r^2 are conducted through the boring w^2 of shaft w^1 . The leads which connect the coils of crown r^2 with the collector rings h^1 , h^2 for the alternating current are conducted 45 through the same boring w^2 of shaft w^1 . The belt pulley i^1 revolves the shaft w^1 in the direction of arrow p^1 .

50 A shaft w^3 with belt pulley i^2 is journaled in the standards d^2 and d^3 in alignment with shaft w^1 . This shaft w^3 is revolved in the direction of arrow p^2 . The disk b with the coil crowns R^1 and R^2 , connected the one with the other by the lead 55 n is keyed upon this shaft w^3 .

Fig. 3^a shows the direction of winding of the coils, and it will be observed that adjacent coils of the same crown are wound 60 in opposite directions, producing alternating poles. The upper view shows conductors g^1 and g^2 which are connected to rings g^1 and g^2 of Fig. 3, for supplying continuous current, and shows conductors h^1 and h^2 for connection to rings h^1 and h^2 .

The lower view illustrates how the coils of the opposite disk may be interconnected.

In order to prevent effects of inductance between the crowns of the same disk a ring O^1 of soft iron is arranged between the 70 crowns r^2 and r^2 and a similar ring O^2 between the crowns R^1 and R^2 , these rings shunting the lines produced by the coils of one crown from the coils of the adjacent crown and thus preventing any substantial 75 inductive action between coils on the same disk.

Fig. 4 shows an arrangement for strengthening the final current which has been weakened by the increase of frequency. 80 Disks 1, 4 and 7 are keyed upon a continuous shaft A . Upon hollow shafts B and B^1 revolving in opposite directions around said shaft A the disk 2 of the first machine, the disks 3 and 5 of the second twin machine 85 and the disk 6 of the third machine are keyed. All disks revolve at exactly the same speed. The currents produced by the individual machines are equal and can be combined by parallel connection to one final 90 current.

I claim:—

1. A high frequency machine comprising two opposed parallel disks, means for rotating said disks in opposite directions, a plurality of circular sets of cores secured to each disk and projecting at right angles to the plane thereof and concentric to the common axis of rotation of said disks, the number of cores in the several sets being equal and the corresponding sets of the two disks being arranged in opposed relation and at the same radial distance from the axis of rotation, a winding on each core, the windings of each set being connected together, means for supplying continuous current to the outer, or first, set of windings on one disk, connections between the outer, or first, set of windings on the other disk and the second set of windings thereof, connections between the second set of windings of the first disk and the third set of windings thereof, and so on, the outer induced and the adjacent inner inducing windings on the same disk being connected, 100 and means for collecting the alternating current induced in the innermost set of windings of the first disk.

2. A high frequency machine comprising two opposed parallel disks, means for rotating one of said disks, a plurality of circular sets of cores on each disk, the number of cores in the several sets being equal and the corresponding sets on the two disks being arranged in opposed relation and at the 110 same radial distance from the common axis of rotation of the disks, a winding on each core and the windings of the same set being connected together, means for supplying continuous current to the outer, or first, set 115 of windings on one disk and the second set of windings on the other disk, connections between the second set of windings of the first disk and the third set of windings thereof, and so on, the outer induced and the adjacent inner inducing windings on the same disk being connected, 120 and means for collecting the alternating current induced in the innermost set of windings of the first disk.

of windings on one disk, connections between the outer, or first, set of windings on the other disk and the second set of windings thereof, connections between the 5 second set of windings on the first disk and the third set of windings thereof, and so on, the outer induced and the adjacent inner inducing windings on the same disk being connected, and means for collecting 10 the alternating current induced in the innermost set of windings of the first disk.

3. A high frequency machine comprising two opposed parallel disks, means for rotating one of said disks, a plurality of circular 15 sets of cores on each disk, the number of cores in the several sets being equal and the corresponding sets on the two disks being arranged in opposed relation and at the same distance from the common axis of 20 rotation of the disks, a winding on each core and the windings of the same set being connected together, means for supplying continuous current to the outer, or first, set of windings on one disk, connections 25 between the outer, or first, set of windings on the other disk and the second set of windings thereof, connections between the second set of windings on the first disk and the third set of windings thereof, and so on, 30 the outer induced and the adjacent inner inducing windings on the same disk being connected, and means for collecting alternating currents from one or more of said induced windings.

35 4. A high frequency machine, comprising two opposed parallel disks, means for rotating said disks in opposite directions, a plurality of circular sets of cores on each disk, the number of cores in the several sets 40 being equal and the corresponding sets of the two disks being arranged in opposed relation and at the same distance from the common axis of rotation of the disks, a winding on each core, the windings on each set being connected together, means for supplying continuous current to a set of windings on one disk, whereby an alternating 45 E. M. F. is induced in the opposed windings on the other disk, said induced windings being connected to an adjacent set of windings on the same disk, whereby these last mentioned windings induce alternating E. M. F. of higher frequency in the opposed windings on the first disk, and so on, the induced and 50 adjacent inducing windings on same disk being connected, and means for collecting alternating current from one or more sets of induced windings.

55 5. A high frequency machine, comprising two opposed parallel disks, means for rotating said disks in opposite directions, a plurality of circular sets of cores on each disk, the corresponding sets on the two disks being arranged in opposed relation and at 60 the same distance from the common axis of 65

rotation, a winding on each core, the windings of each set being connected together, means for supplying continuous current to a set of windings on one disk, whereby alternating E. M. F. is induced in the opposed 70 windings of the other disk, said induced windings being connected to an adjacent set of windings on the same disk, whereby these last mentioned windings induce alternating E. M. F. of higher frequency in the opposed 75 windings of the first disk, and so on, the induced and adjacent inducing windings of the same disk being connected, and means for collecting alternating current from one or more sets of induced windings. 80

85 6. A high frequency machine comprising a shaft, a support fixed to said shaft, a plurality of circular concentric sets of cores fixed on said support, a winding on each core, the windings of each set being connected together, a second shaft coaxial with said first shaft, a support fixed to said second shaft carrying a plurality of circular concentric sets of cores each of which is provided with a winding and the windings of each set being connected together, corresponding sets of windings on the two supports being arranged in inductive relation, means for supplying continuous current to a set of windings on one of said supports, whereby an alternating E. M. F. is induced in the corresponding set of windings on the other support, said induced windings being connected to an adjacent set of windings on the same support, whereby these last mentioned windings induce alternating E. M. F. of higher frequency in the corresponding windings of the first support, and so on, the induced and adjacent inducing windings of the same support being connected, means for 90 rotating said shafts in opposite directions, and means for collecting alternating current from one or more sets of induced windings. 95

100 7. A high frequency machine comprising two opposed parallel disks, means for rotating said disks in opposite directions, at least two circular concentric sets of cores on each disk, the corresponding sets on the two disks being arranged in opposed relation and at the same distance from the common axis of 105 rotation, a winding on each core, the windings of each set being connected together, means for supplying continuous current to a set of windings on one disk, whereby alternating E. M. F. is induced in the opposed winding of the other disk, said induced windings being connected to the adjacent set of windings on the same disk, whereby these last mentioned windings induce alternating 110 E. M. F. of higher frequency in the opposed windings of the first disk, and means for collecting the induced alternating current. 115

120 8. A high frequency machine comprising a plurality of circular concentric sets of cores each provided with a winding and the 125

windings of each set being connected together, a plurality of circular concentric sets of cores arranged in opposed relation to said first mentioned sets each provided with a winding and the windings of each set being connected together, means for rotating one of said plurality of sets with respect to the other, means for supplying continuous current to one set of windings, whereby alternating E. M. F. is induced in the opposed set of windings, said induced windings being connected to an adjacent set of windings, whereby these last mentioned windings induce alternating E. M. F. of higher frequency in the windings opposed thereto, and

so on, each set of induced windings being connected to the adjacent set of inducing windings, whereby mirror-excitation of the windings is produced with progressive increase in the frequency of the induced alternating E. M. F., and means for collecting alternating current from one or more sets of induced windings.

In testimony whereof I affix my signature in presence of two witnesses.

GÜNTHER KRAWINKEL.
